COMPRESSOR UNLOADING MEANS

Otto A. Labus, Emil T. Neubauer, and Robert G. Miner, La Crosse, Wis., assignors to The Trane Company, La Crosse, Wis.

Application November 14, 1949, Serial No. 127,016

3 Claims. (Cl. 230—25)

1

This invention relates to compressors and to the control of compressors in refrigeration systems of the type having a compressor, a condenser and an evaporator. An object of the present invention is to provide a compressor which may be controlled to operate at its maximum capacity or at one of several fractional amounts of its maximum capacity without any substantial change in speed.

Another object of this invention is to provide a compressor in which the unloading mechanism and its control are energized by the lubrication system of the compressor.

A third object of our invention is to provide a compressor including unloading means therefor which is inexpensive to manufacture and easy to assemble and repair.

A further object of our invention is to provide means to control the operation of the compressor according to conditions of the refrigeration system of which it is a part.

Still another object of the invention is to provide a compressor unloading mechanism which is responsive to the starting mechanism of the motor which drives the compressor.

Other objects and advantages of the invention will be clearly apparent as the specification proceeds to describe the invention with reference to the accompanying drawings in which—

Fig. 1 is a sectional view, more or less diagrammatic, of the apparatus of this invention.

Fig. 2 is a cross-sectional view of a cylinder showing a modification of my invention.

Fig. 3 is a sectional view taken on the line 3—3 of Fig. 1.

Fig. 4 is a top plan view of the cylinder liner of the form of the invention shown in Fig. 1.

Fig. 5 is a top plan view of cylinder liner and valve lifting sleeve of the form of the invention of Fig. 2.

Fig. 6 is a side view of the valve lifting sleeve of the form of the invention shown in Fig. 2.

Fig. 7 is a diagrammatic view of the compressor motor wiring and the compressor oil piping.

Fig. 8 is a sectional view taken on a plane through the axes of the cylinders of the compressor.

Referring now to Fig. 1, numeral 10 designates the body or block of the compressor in which is rotatably mounted a crankshaft 12 which is driven by an electric motor or an internal combustion engine or other suitable power means. The compressor may have any desired number of cylinders, and any desired arrangement of cylinders. The cylinders may be arranged radial, in line or in a V. These cylinder arrangements are

old and well known and do not constitute part of this invention. For purposes of illustration and description it will be assumed that the compressor has four cylinders.

Connecting rods 14 are rotatably connected at one end to the crankshaft 12 and they are pivotally connected at the other end to each of the pistons 16. Each cylinder comprises a cylinder liner 18 which is inserted from the outer end of the cylinder before the valve plate 20 and the cylinder head 22 have been mounted in place. The cylinder liner is supported at its outer end by the outer wall 24 of the cylinder and at its inner end by the wall 26 of the suction manifold 28 which communicates with the associated refrigerating system through a suction line 30 which is shown diagrammatically. The suction manifold 28 also communicates with the crankcase 32 through a plurality of check valves 34. When the compressor is started the pressure in the suction manifold drops rapidly and the difference in pressure between the crankcase 32 and the suction manifold 28 closes the check valve 34 and prevents a sudden drop in pressure in the crankcase which would cause the oil to foam excessively and form a large volume of foam. Due to leakage of gas from the crankcase 32 to the suction manifold 28 the pressures in these spaces soon become substantially equal, and the check valve opens to allow any oil accumulation in the suction manifold to drain back into the crankcase.

The cylinder liner 18 has a plurality of suction valve ports 36 annularly spaced around its wall. When the piston 16 descends and the suction valve 38 opens, gas flows from the suction manifold through ports 36 into the cylinder. The suction valve 38 is urged toward its seat by a plurality of coil springs 40 which are located in pockets in the valve plate 20. When the piston 16 ascends, the discharge valve 42 opens against the action of springs 44 positioned in a discharge valve cage 46. A discharge valve seat 48 is secured to the discharge valve cage 46 by a nut 50.

The discharge gas from the chambers 52 of the heads 22 is manifolded to a single discharge line 54 which is shown diagrammatically. Line 54 is connected to a condenser 56 which in turn is connected to a liquid receiver 58. Liquid from the receiver flows through an expansion valve 60 to a heat exchanger 62. The matter to be cooled such as air or water flows through conduit 64 in the direction shown by the arrow.

In order to operate the compressor at substantially constant speed, but at increments of its full capacity, we have provided means for holding

one or more suction valves in open position to render the cylinders served by said valves inoperative in compressing gas.

Referring to Fig. 1 and Fig. 4, the cylinder liner 18 has a plurality of holes 66 which support pins 68 for sliding movement. Springs 70 act against heads on the pins 68 to urge the pins downwardly away from the valve 38. A cylinder seal ring 72 is held against upward movement with respect to cylinder liner 18 by a snap ring 74 which engages in a groove in the cylinder liner 18. A cylinder member 76 is supported on the outside of cylinder liner 18, and it is further supported at its end by the lower wall 26 of suction manifold 22. The cylinder member 76 has a plurality of spring pockets which receive a plurality of springs 78 which act against a piston 80. The piston 80 supports a flat ring 82 which in turn supports the pins 68. Cylinder 76 has a hole 84 through which oil under pressure will flow from fitting 86 when the cylinder is to be loaded. A cylinder is loaded by allowing the suction valve to operate so that the cylinder compresses gas. The oil flows from hole 84 through recess 88 in the wall of cylinder liner 18. From recess 88 the oil flows through holes 90 in cylinder 76 into the oil cylinder space and moves piston 80 downwardly against the action of springs 78. Downward movement of piston 80 allows springs 70 to move pins 68 and ring 82 down. When pins 68 move down they allow suction valve 38 to open and close in its normal manner and the cylinder is operating to compress gas or is what is commonly called "loaded." Cylinder seal ring 72, cylinder 76 and piston 80 may all be provided with O-rings as shown. Said O-rings are of some flexible material such as rubber and prevent leakage of oil between the parts.

The operation of the control mechanism will now be described. A reservoir of oil 92 is contained in the bottom of the crankcase 32. The oil from reservoir 92 is used to lubricate the compressor and operate the unloading mechanism. An oil pump shown diagrammatically at 94 has an inlet pipe 96 extending down into the oil reservoir. It should be understood that the oil pump 94 may be driven in any suitable manner. For instance it may be located at the end of the crankshaft and connected to be driven by the crankshaft. This is an old and well known expedient. The oil flows from pump 94 to a check valve 98 which maintains a constant pressure in the oil system and returns the excess oil to the reservoir through pipe 100. From check valve 98 the oil under pressure flows through a pipe 102. Pipe 102 has a branch pipe 104 connected thereto. Branch pipe 104 supplies lubricating oil to various parts of the compressor such as the shaft seal and the bearings. The oil flows from pipe 102 to a solenoid operated valve 106 the operation of which will be described later. A pipe 108 conducts oil from the solenoid valve 106 to a valve body 109 of a valve indicated generally by numeral 110. The valve 110 is secured to the block 10 of the compressor and extends into the crankcase 32. The pipe 108 has a branch pipe 112 which conducts oil to the unloading cylinder 76 of one of the compressor cylinders which is therefore always loaded whenever the solenoid valve 106 is open. The other three cylinders are loaded or unloaded according to the refrigerant requirements of the system as will presently be described. The pipe 108 is connected to passageway 114 in the valve body 109. Passageway 114 connects with valve bore 116 in the valve body

109. A plunger 118 has a sliding fluid tight fit in bore 116. Plunger 118 has a small hole 120 drilled in one end for the passage of oil through the hollow center of nut 122. Nut 122 has a nozzle 124 from which the oil flows in varying amounts according to the position of screw 126 which is in threaded engagement with arm 128. The operation of arm 128 will be described later in the specification. It may thus be seen that a small quantity of oil is allowed to escape from bore 116 through hole 120, nut 122 and nozzle 124. The rate of escape of oil determines the pressure in bore 116 tending to force plunger 118 to the left in Fig. 1. A spring 130 is supported on stud 132 which is in threaded engagement with the valve body 109 and urges plunger 118 to the right in Fig. 1 against the oil pressure tending to urge plunger 118 to the left. The bore 116 of the valve body 109 has three grooves 134, 136, and 138. As plunger 118 moves to the left in Fig. 1 grooves 134, 136 and 138 are successively connected with the oil pressure in bore 116. Grooves 134, 136, and 138 are connected with pipes 140, 142, and 144 respectively. Pipe 140 is connected to one of the unloader cylinders 76 as shown in Fig. 1. In like manner pipes 142 and 144 are connected to the unloader cylinders 76 of other cylinders of the compressor. A pipe 146 is connected with the valve bore 116 to provide for the return of oil to the crankcase 32.

The valve body 109 contains a bellows 148 which controls the position of plunger 118 as will now be described. The bellows 148 is clamped to the valve body 109 by a plug 150 which is in threaded engagement with the valve body 109. Inside the bellows is a spring 152 which bears at one end against an abutment 154 which is soldered or brazed to the end of the bellows 148. At its other end the spring bears against an abutment 156 which in turn is held against the spring by a screw 158 threaded into cover 160 of valve 110. A cover 162 is threaded on a boss of cover 160 to provide a seal for screw 158. The chamber 164 in which the bellows 148 is mounted is connected by a passageway 166 to the suction manifold 28 of the compressor whereby the pressure on the outside of the bellows is substantially suction pressure. The interior of the bellows 148 is connected by a passageway 168 and a pipe 170 to a pneumatic temperature controller 172 which is connected to a source of air under pressure 174. A thermostatic bulb 175 is supported in the conduit 64 in the path of the matter leaving the heat exchanger 62. The thermostatic bulb 175 is connected by tube 176 to pneumatic temperature controller 172. The pneumatic temperature controller 172 is a standard device well known to those skilled in the art, and since it forms no part of the invention per se, its construction will not be described in detail. A pin 177 is slidably mounted in valve body 109 and is engaged at one end by abutment 154 of bellows 148. The other end of pin 177 engages arm 128 which is pivoted to bracket 178 by pin 180 which extends through the bracket 178 and the arm 128. Bracket 178 is fastened to the valve body 109 in any suitable manner. The bracket 178 and the arm 128 have a plurality of holes for receiving the pin 180 to provide for moving the pivotal point of arm 128 by shifting the pin 180 to a different set of holes. A member 182 is secured to bracket 178 in any suitable manner as by spot welding and supports a spring 184 which at its other end presses against the arm 128. Referring to Figure 3, the plunger 118 has

four round bottomed grooves 186 which are engaged by balls 188 which in turn are urged to seat in the grooves 186 by the springs 190 which are held in place by screws 192 which are in threaded engagement with the valve body 189. Balls 188 by engaging in grooves 186 insure that plunger 118 will move in definite steps to completely uncover or completely close each of the grooves 134, 136, and 138 to oil pressure.

Figs. 2, 5, and 6 show a modified form of the hydraulic valve lifting mechanism. In this form of the invention a piston 194 in the form of cylindrical shell surrounds the cylinder liner 18 and is mounted for sliding movement thereon. Piston 194 has at one end a plurality of fingers 196 which extend upwardly through the suction valve ports 36 to engage the suction valve 38 and hold it open during certain conditions of operation of the compressor as will be described. A rubber O-ring 198 is supported on a flange 200 of the piston 194 and prevents leakage of oil around the piston. A ring 202 closes the end of the cylinder and a rubber O-ring 204 prevents leakage around the ring 202. The ring 202 is held against upward movement by a spring snap ring 206 which by its resiliency engages in a groove 208 in the wall 26 of the suction manifold 28. The snap ring 206 has two ears 210 which are pressed toward each other to mount the snap ring 206 in the groove 208 or to remove it therefrom. A spacer ring 212 channel shaped in cross-section is mounted between the O-rings 198 and 204 to prevent the O-rings 198 and 204 from moving to a position at which they would close the oil supply opening 214. Springs 216 are supported in holes in wall 26 and act against the flange 200 to urge the piston 194 upwardly against the valve 38. When the control mechanism admits oil under pressure to pipe 140, the oil flows through opening 214 and forces O-ring 198 and piston 194 downwardly to allow the suction valve 38 to operate in its normal manner.

Fig. 7 is a diagrammatic view showing the wiring of the compressor motor starter and the oil piping of the compressor. For the purpose of explanation it will be assumed that the compressor is driven by a three phase motor 218 having a two step primary resistance reduced voltage starter. A conventional motor starter is shown having three resistors 220 bridged by a three pole contactor having contacts 222. This contactor has an auxiliary contact 224 which is in series with the solenoid valve 106. An additional three pole contactor having contacts 226 is connected to supply current from the supply lines 228 to the resistors 220. The contacts 226 have an operating coil not shown and the contacts 222 and 224 also have an operating coil not shown. Conventional auxiliary circuits provide the sequence of operation by which contacts 226 are first closed, and, after the motor has started, contacts 222 and 224 are closed.

When the compressor motor 218 is started the contacts 226 close and current flows from the supply lines through the resistors 220 to the motor 218. During this period, contacts 222 and 224 are open and no current is supplied to the solenoid valve 106 and solenoid valve 106 is therefore closed. With solenoid valve 106 closed oil pressure does not reach any of the unloading cylinders 76 and the compressor is completely unloaded. As the timing device in the auxiliary circuits completes its cycle, the contacts 222 and 224 close, short circuiting the resistors 220 and supplying motor 218 with current directly from

the lines 228. When contact 224 closes, the circuit to solenoid valve 106 is completed and solenoid valve 106 opens allowing oil to reach line 112 and valve 110 to load all of the compressor cylinders.

Modus operandi

Having thus described the details of construction of the apparatus, the manner of operation will now be described:

When the compressor motor starting contacts 226 are closed, the solenoid valve 106 is not energized and lines 108 and 112 do not receive any oil. None of the valve lifting cylinders 76 is receiving oil. Consequently the springs 78 acting through piston 80, rings 82 and pins 68 are holding the suction valves 38 of all cylinders in open position. When the motor starter completes its cycle, solenoid valve 106 is energized and oil pressure reaches lines 108 and 112. Since the suction pressure in manifold 28 is high during starting, the bellows 148 is compressed and screw 126 closes opening in nozzle 124 to raise the pressure in valve bore 116 and move plunger 118 to its extreme position to the left as viewed in Fig. 1. With the plunger 118 in this position, oil flows from pipe 108 through passageway 114 and into grooves 134, 136 and 138 and then into pipes 140, 142, and 144. Since the pipes 112, 140, 142, and 144 are each connected to one of the fluid cylinders 76 serving each of the compressing cylinders 18, the pistons 80 of the cylinders 76 are all forced downwardly by oil pressure, and the springs 78 force the pins 68 downwardly so that the suction valves 40 are allowed to operate in their normal manner so that all the cylinders are loaded and the compressor is operating at its full capacity. After the compressor has been operating for a period of time, the refrigeration system served by the compressor becomes cooled to the design temperature and the suction pressure tends to fall below the design pressure. When the suction pressure drops below a predetermined point which may be set as desired by adjusting screw 158, the bellows 148 expands and acts through pin 177 and arm 128 to move screw 126 away from nozzle 124 and allow a sufficient amount of oil to pass through nozzle 124 to reduce the pressure in bore 116 to the point at which spring 130 moves plunger 118 to close groove 138 from oil pressure and open pipe 144 to the drain 146. The cylinder served by pipe 144 therefore becomes unloaded, because springs 78 acting through piston 80, ring 82, and pins 68 holds the suction valve 40 open. If the capacity of the three loaded cylinders is greater than the load on the refrigeration system, the tendency of the suction pressure to drop will continue, and the bellows 148 will expand further until pipe 142 is cut off from the oil pressure and connected to the drain pipe 146. Two of the four cylinders have thus been unloaded. If the capacity of the two loaded cylinders is greater than the refrigeration load, the third cylinder will be unloaded in the same manner as the first two cylinders were unloaded. The fourth and last cylinder which is served by pipe 112 always remains loaded except for the starting period when solenoid valve 106 is closed. It is usually advisable during operation of the compressor to keep at least one cylinder loaded in order to prevent the compressor from overheating.

The thermostatic bulb 175 being exposed to the matter leaving coil 62 is responsive to the temperature of said matter and causes the pneu-

matic temperature controller 172 to operate in a manner which will now be described. By way of example let us assume that the unloading control is set to maintain a suction pressure not lower than 40 pounds per square inch. The pneumatic temperature controller 172 will vary the suction pressure above or below 40 pounds per square inch as the temperature of the matter leaving coil 62 falls below or rises above a desired temperature.

Let us assume that the bulb 175 is subjected to a temperature above that which is desired. The pneumatic temperature controller 172 will reduce the pressure in pipe 170 and will therefore reduce the pressure inside bellows 148. With a reduced pressure inside bellows 148 the suction pressure must drop below 40 pounds per square inch to unload the compressor. Therefore a suction pressure below 40 pounds per square inch is maintained and the lower suction pressure causes the coil 62 to do more work and to bring the temperature of the matter leaving coil 62 down to the desired temperature.

Although we have described in detail the preferred embodiments of our invention, we contemplate that many changes may be made without departing from the scope or spirit of our invention, and we desire to be limited only by the claims.

We claim:

1. A compressor comprising a plurality of compressing cylinders, a common suction chamber and a common compression chamber, each of said compressing cylinders having associated therewith a suction valve through which gaseous medium may be admitted from said suction chamber and a discharge valve through which compressed gaseous medium may be discharged into said compression chamber, and spring means to force the suction valve to open position, fluid pressure means for overcoming said spring means, said fluid pressure means comprising an annular piston slidably mounted on the outer surface of said compressing cylinder in fluid sealing relationship therewith and providing an annular fluid chamber between said annular piston and the outer surface of said compressing cylinder, fluid pressure creating means, means comprising a valve for conducting said fluid pressure from said fluid pressure creating means to said annular fluid chamber, and means responsive to the pressure in said suction chamber for controlling said fluid pressure conducting valve to cut off the supply of fluid pressure to said annular fluid chamber.

2. A compressor comprising a plurality of compressing cylinders, a common suction chamber and a common compression chamber, each of said compressing cylinders having associated therewith a suction valve through which the gaseous medium may be admitted from said suction chamber and a discharge valve through which compressed gaseous medium may be discharged into said compression chamber, means

comprising an annular piston slidably mounted on the outer surface of said compressing cylinder in fluid sealing relationship therewith and providing an annular fluid chamber between said annular piston and the outer surface of said compressing cylinder, valve engaging means supported by said annular piston, spring means acting against said annular piston and tending to move said annular piston and said valve engaging means toward said suction valve to force said suction valve to open position, fluid pressure creating means, means comprising a valve for conducting the fluid pressure from said fluid pressure creating means to said annular fluid chamber to force the annular piston in a direction away from said suction valve against the force of said spring means and means responsive to the pressure in said suction chamber for controlling said fluid pressure conducting valve to cut off the supply of fluid pressure to said annular fluid chamber.

3. A compressor comprising a plurality of compressing cylinders, a common suction chamber, and a common compression chamber, each of said compressing cylinders having associated therewith a suction valve through which gaseous medium may be admitted from said suction chamber and a discharge valve through which compressed gaseous medium may be discharged into said compression chamber, and spring means to force the suction valve to open position, fluid pressure means for overcoming said spring means, said fluid pressure means comprising an annular piston slidably mounted on the outer surface of said compressing cylinder in fluid sealing relationship therewith and providing an annular fluid chamber between said annular piston and the outer surface of said compressing cylinder, fluid pressure creating means, means comprising a valve for conducting said fluid pressure from said fluid pressure creating means to said annular fluid chamber, fluid means for moving said fluid pressure conducting valve to closed position to cut off the supply of fluid pressure to said annular fluid chamber and means responsive to the pressure in said suction chamber for controlling said fluid means.
